UNITED STATES PATENT OFFICE.

GEORGE P. FENNER, OF NEW LONDON, CONNECTICUT.

UNIVERSAL JOINT.

SPECIFICATION forming part of Letters Patent No. 364,503, dated June 7, 1887.

Application filed March 31, 1887. Serial No. 233,148. (No model.)

To all whom it may concern:

Be it known that I, GEORGE P. FENNER, a citizen of the United States, residing at New London, in the county of New London and State of Connecticut, have invented new and useful Improvements in Universal Joints, of which the following is a specification.

This invention relates to improvements in universal joints, as set forth in the following specification and claim, and illustrated in the accompanying drawings, in which—

Figure 1 is a side elevation of a universal joint. Fig. 2 is a section in the plane $x x$, Fig. 1. Fig. 3 is a section in the plane $y y$, Fig. 1.

Similar letters indicate corresponding parts.

In the drawings, the letter A designates a fork. Within the fork A is placed a block, C. A bolt, D, passes through the fork A and the block C.

B is another fork, which sits about the block C, as seen in the drawings. A bolt, E, passes through the fork B, the block C, and the bolt D. The bolts D E may be of any suitable construction—such, for example, as screw-bolts provided with heads and nuts. As the bolt E passes through the bolt D the bolt E holds the

bolt D in place, even if the nut of the bolt D should become loosened or removed by strain or by accident.

The bolts D E prevent spreading of the forks A B, and the block C prevents compression of the forks A B. The said forks are thus protected against breakage through any severe strain brought to bear upon them.

What I claim as new, and desire to secure by Letters Patent, is—

The combination, with the forks A B, of the block C, fitting both forks, the bolt D, made to extend through the fork A and the block C, and held in position by its head at one end, its nut at the opposite end, and the bolt E, made to extend through the fork B, the block C, and the bolt D, said bolt E being held in its place by its head at one end and its nut at the opposite end, substantially as set forth.

In testimony whereof I have hereunto set my hand and seal in the presence of two subscribing witnesses.

GEORGE P. FENNER. [L. S.]
